UNITED STATES PATENT OFFICE.

FRANK PARLANTE, OF BROOKLYN, NEW YORK.

SHOE.

Application filed August 18, 1928. Serial No. 300,501.

This invention relates to shoes, and while the invention is particularly adapted for use in connection with the manufacture of ladies' slippers and low shoes, I do not wish 5 to be limited to the particular type of shoe.

An object of the invention is to provide in a turned shoe a half sole and a counter which forms the heel and shank of the shoe, joining with the half sole and dispensing 10 with the necessity for a complete sole extending under and forming the shank of the shoe.

A further object is to provide in a turned shoe of this character an improved construction and arrangement of half sole and counter together with the upper and other portions of the shoe, so as to form a shoe which will be extremely light in weight and comfortable to the wearer and provide all necessary support as well as to form a shoe of 20 most attractive appearance.

With these and other objects in view, the invention consists in certain novel features of construction and combinations and arrangements of parts, which will be more fully hereinafter described and pointed out in the claims.

In the accompanying drawings—

Figure 1 is a perspective view showing my 30 improved shoe in the course of manufacture;

Figure 2 is a view in side elevation of the completed shoe turned right side out;

Figure 3 is an exaggerated view in section on the line 3—3 of Figure 1;

Figure 4 is a perspective view of my improved counter;

Figure 5 is a view in side elevation of the completed shoe having parts broken away to show the sole in longitudinal section;

Figure 6 is a bottom plan view of the shoe;

Figure 7 is a view in transverse section on the line 7—7 of Figure 5.

In carrying out my invention, I provide a half sole 1, and I term this part 1 a "half sole" because it is designed to cover the toe and ball portion of the foot only and does not extend under the shank of the shoe as is common with a complete sole such as ordinarily employed.

In connection with a half sole of this type I employ a counter 2 which forms both the heel and the shank of the shoe. This counter 2 is made of leather or any other sufficiently stiff and pliable material, preferably formed 55 from a single piece bent intermediate its

ends to form a heel portion 3 and joined at its inner adjacent edges throughout the major portion of its length, as shown at 4. The joined edges or portions of the shank by the line of stitching 4 constitute a strengthening web extending throughout the shank of the shoe and also provide a means or place of attachment for the upper of the shoe. 60

The forward free end of the counter is 65 flexible and free for manipulation and attachment to the half sole 1 and extends around the half sole as far as may be desired.

The shoe lining 5 and the outer or body portion of the shoe 6 are of any suitable flexible material such as is commonly employed 70 in the manufacture of shoes, and they are both secured to the half sole 1 and also to the counter 2.

A preferable means of securing these parts to the counter is to project the edges 75 of the outer or body portion 6 of the shoe between the sections of the counter and secure them by the line of stitching 4. The lining 5 also may be secured to the counter by an adhesive or any other suitable means, 80 and also may be secured by the same line or an additional line of stitching as that indicated by the reference numeral 4.

When the shoe is reversed an inner 85 strengthening sole 7, constituting a strip or series of connected strips of any desired rigidity, may be cemented or otherwise secured in the shoe and preferably extend from the heel portion over the shank and along the half sole as far as desired and a soft 90 covering piece 8 is secured over this strengthening strip 7.

The exact manner of joining the lining and upper to the sole and the counter may 95 of course be varied without departing from the invention.

The broad idea of the invention is the provision of a counter which joined to a half sole forms the shank as well as the heel of the shoe and dispenses with the employment 100 of a sole extending under the shank, which is common practice.

I of course provide a supporting heel 9 which may be attached to the heel of the shoe in any approved manner and I may 105 ornament and construct the shoe upper in any way desired.

In manufacturing the shoe, the parts are assembled, as illustrated in Figure 1. The counter 2 at its forward end is secured di- 110

rectly to the half sole 1, and the lining 5 and upper outer covering 6 of the shoe are also stitched to the half sole and to the counter. The shoe is then reversed and the 5 insoles 7 and 8 are inserted and the heel 9 attached.

A shoe of this type is extremely light in weight in use and has sufficient strength and rigidity to withstand all necessary strains to 10 which it is put.

Various changes and alterations might be made in the general form of the parts described without departing from my invention and hence I do not limit myself to the 15 precise details set forth but consider myself at liberty to make such changes and alterations as fairly fall within the spirit and scope of the appended claims.

I claim:

- 20 1. A turned shoe, comprising a half sole, a counter forming the heel and shank of the shoe and secured to the half sole, and a lining and upper secured to the half sole and to the counter.
- 25 2. In a shoe, the combination with an upper, a counter forming the heel of the shoe

and also the shank of the shoe, and a half sole secured to the upper and to the forward end of the counter.

3. In a turned shoe, the combination with 30 a half sole, of a counter extending from the heel to the half sole and throughout the shank of the shoe, said counter being formed of a single piece of material connected by a line of stitching extending centrally of the 35 counter and along the shank, and a lining and upper secured to the half sole and to said counter adjacent said line of stitching.

4. In a turned shoe, the combination with 40 a half sole, of a counter extending from the heel to the half sole and throughout the shank of the shoe, said counter being formed of a single piece of material connected by a line of stitching extending centrally of the counter and along the shank, and a lining 45 and upper secured to the half sole and to said counter adjacent said line of stitching, the portions of the counter joined by the line of stitching forming a strengthening web longitudinally of the counter.

FRANK PARLANTE.
